[57] CLAIM

The ornamental design for a combined table place mat and napkin holder, substantially as shown and described.

DESCRIPTION

FIG. 1 is a rear elevational view of a combined table place mat and napkin holder showing my new design; FIG. 2 is a side elevational view of FIG. 1; FIG. 3 is a top plan view of FIG. 1; FIG. 4 is a front elevational view of FIG. 1; FIG. 5 is a rear elevational view of a modified embodiment of the design of FIGS. 1 and 4, the only difference residing in the configuration of the front plate.
